UNITED STATES PATENT OFFICE.

EDMOND LEDOUX, OF SHEFFIELD, ENGLAND, ASSIGNOR TO SIMON-CARVES BYE-PRODUCT COKE-OVEN CONSTRUCTION AND WORKING COMPANY LIMITED, OF MANCHESTER, ENGLAND.

COKING-OVEN.

No. 904,268.

Specification of Letters Patent.

Patented Nov. 17, 1908.

Application filed February 10, 1906. Serial No. 300,414.

To all whom it may concern:

Be it known that I, EDMOND LEDOUX, a citizen of the French Republic, and a resident of Sheffield, in the county of York, 5 England, have invented certain new and useful Improvements in Coking-Ovens, of which the following is a specification.

These improvements relate to coking ovens of that known type in which each gas 10 canal is led under a series of vertical heating flues, and the air flues are arranged longitudinally below the coking chambers and open into the vertical flues at a higher 15 level than the gas nozzles. The air flues may be used for alternatively carrying air for gas combustion and for conducting waste gases, or they may be used solely and continuously for the passage of air.

The main object of this present invention 20 is to provide means for easily and effectively regulating the dampers or the like controlling the gas and air inlets to the heating flues, which means are easily operable from the front of the oven. Passages 25 under the ovens to provide access to the different dampers or the like which have hitherto been employed are thus not necessary, and the expensive foundations of the 30 ovens which have before been employed may be dispensed with.

This invention also dispenses with the 35 openings through brickwork in the top of each heating flue to obtain access to the above dampers or the like. The air and gas in a heating flue do not come into contact 40 with each other until they are some distance above the gas nozzle so that combustion does not take place below this point of contact, and the heat is most usefully applied to the 45 coking chambers.

Part of a coking oven constructed according 50 to these improvements is shown in the accompanying drawings.

Figure 1 illustrates it in vertical section 55 transverse to the air and waste gas flues and the gas canals. Fig. 2 illustrates it in vertical section at right angles to Fig. 1, being taken on line A—B of Fig. 1. Fig. 3 indicates a section along the lines C—D of Fig. 50 1. Fig. 4 shows a section along the line E—F, Fig. 1.

a indicates one of a series of heating flues, 60 *b* *b* coking chambers, *c* *c* air or air and waste gas flues each communicating with its own flue *a*, *d* a gas canal, and *e* *e* cooling canals.

Any suitable number of these flues, chambers, and canals may be used in combination to form a complete oven.

f indicates a longitudinal gas inlet or slot extending the length of the gas canal and by 60 means of which gas may enter the flues *a*. This slot or longitudinal opening is covered throughout its length by firebrick slabs *g* each formed with an opening or perforation *g'* for the passage of the gas. These slabs or 65 bricks may be removed from the oven through the closable opening *h* in the front of the oven by means of a suitable tool, and may be substituted by slabs or bricks having different sized openings. The gas supply to 70 the flues can thus be easily adjusted. Incoming gas from a gas opening *g'* passes upwards through the branch *a'* to the flue.

Referring to the flue *c*, in its use for supplying air to burn the gas, *k* is an opening 75 through which air from the flue *c* may pass upwards through the branch *a''* to the flue *a*.

l l indicate firebrick slabs or bricks by means of which the different openings *k* may have their areas varied or by means of which such openings may be closed or opened. The slabs are easily moved by a suitable tool inserted through the closable openings *m* in the oven front. (Fig. 3). One form of the slab or brick dampers is shown on the left of 80 Fig. 3. Another form is shown on the right hand side of the same figure, and this form may be provided with holes or openings as are the dampers described as usable with the gas inlet opening and in combination with 85 such dampers the wall of the flue may be provided with projections *n* which will act as guides to guide the dampers to their correct positions.

The branches *a'* *a''* of the flue *a* as shown 90 in Fig. 1 are formed by the partition or wall *p*. The gas and the air do not come together until they have reached the top of the wall, and combustion does not take place below 95 this point and the heat of the flame is thus most usefully applied to heating the coking chambers.

What I do claim as my invention and desire to secure by Letters Patent is:—

1. In a coking oven, the combination of a 100 series of vertical heating flues, a gas canal below such flues, a gas opening therefrom leading to each flue, a series of adjustable dampers for regulating the supply of gas 105 and operable from the front of the oven, and 110

2
an opening in the oven front through which a suitable implement may be inserted to operate any one of the series of dampers, substantially as described.

- 5 2. In a coking oven, the combination of different series of vertical heating flues, coking chambers disposed between such series of flues, air flues disposed longitudinally below the coking chambers, passages between the 10 air flues and heating flues, dampers for adjusting such passages from the oven front, openings in the oven front through which such dampers can be operated, gas canals disposed longitudinally below the series of

vertical heating flues, openings to permit gas to enter the different series of flues from their gas canals, dampers for regulating the gas supply and operable from the oven front, and openings in the oven front through which such dampers may be operated. 15

In testimony whereof I have signed my name to this specification in the presence of two subscribing witnesses. 20

E. LEDOUX.
